UNITED STATES PATENT OFFICE.

WILLIAM H. BATES AND ROBERT C. DOUGLASS, OF CHICAGO, ILLINOIS,
ASSIGNORS TO THE MARINE IRON WORKS, OF CHICAGO, ILLINOIS, A
CORPORATION OF ILLINOIS.

VARIABLE CUT-OFF FOR STEAM-ENGINES.

SPECIFICATION forming part of Letters Patent No. 738,147, dated September 8, 1903.

Application filed September 25, 1902, Serial No. 124,725. (No model.)

To all whom it may concern:

Be it known that we, WILLIAM H. BATES and ROBERT C. DOUGLASS, both citizens of the United States of America, residing at Chicago, in the county of Cook and State of Illinois, have jointly invented certain new and useful Improvements in Variable Cut-Offs for Steam-Engines, of which the following is a description.

10 Our invention belongs to that class of devices in which a supplemental steam and valve chest is provided for controlling the admission of the steam to the main steam-chest.

It has for its object the construction of suitable mechanism for controlling the length, position, or lead of the supplemental valve and simultaneously therewith to control the length of the throw or travel of the same.

To this end our invention consists in the 20 novel construction, arrangement, and combination of parts herein shown and described, and more particularly pointed out in the claims.

In the drawings, wherein like reference 25 characters indicate like or corresponding parts, Figure 1 is a side elevation of a horizontal marine engine equipped with our invention. Fig. 2 is a top plan of the same in partial section to show the arrangement. Fig. 3 is a detail view of the controlling mechanism for the supplemental valve, taken in the line 3 3 of Fig. 5. Fig. 4 is a similar view showing the parts in a different position, and Fig. 5 is a top plan of the same.

30 In the drawings, 1 represents the main steam-chest for the cylinder 2, provided with any preferred form of valve mechanism. As shown, the valves 3 3 are connected by the stem 4 and operated by its engagement with the rocker-arm 5 in the usual manner. Beside the main valve-chest is arranged a supplemental valve-chest of any well-known type. As shown, the cylinders 6 6 are provided with piston-valves 7 7, each mounted 45 upon a part of the valve-rod 8, which is formed in two parts. By thus dividing the valve 8 the length, position, or lead of the

valve may be regulated as desired. The object of the supplemental valve-chest and its mechanism is to regulate the admission of 50 steam to the main valve-chest, or, in other words, to regulate the "cut-off." By our device this can be effectually accomplished without throttling or wire-drawing the steam or in any way narrowing the steam-ports during 55 the period of admission thereto.

As shown in the drawings, 9 is a plate or equivalent lever or part, preferably circular in form and so supported in any convenient manner as to oscillate or freely revolve upon 60 its center 10. The plate or the disk 9 is actuated by an eccentric-rod 11 or equivalent means to impart a swinging or oscillating movement thereto, said movement being regulated in relation to the stroke of the engine. 65

As shown, the eccentric-rod 11 is pivotally secured to the pin 12, positioned in the disk 9. In the preferred form the disk 9 is provided with a set of guides 13 13, arranged to receive a small cross-head 14, so arranged 70 that the cross-head may by any convenient means be shifted radically toward and from the center or fulcrum of the disk. The cross-head 14 is provided with two levers 15 15, pivotally connected thereto and secured to the 75 rod 8 8 in such a manner that the levers 15 15 and their connections will form a toggle-lever device, as shown in Fig. 3. Upon moving the cross-head 14 outward the action of the toggle-lever will serve to separate or part the 80 rods 8 8 and the valve, and thus vary the position or lead of the valves, as shown in Fig. 4.

16 is a sleeve within which the free ends of the rods 8 8 are inserted and which serves to retain them in alinement with one another. 85

It will be readily seen that the throw or travel of the supplemental valve will also be regulated by the position of the cross-head 14 within the guides 13 13—that is to say, by the distance of said cross-head from the center or fulcrum 10 of the supporting disk or lever. Thus as the cross-head is moved outward from the center the toggle connection will simultaneously cause the stems 8 8 to be

separated, and thus lengthen the valve, the single operation accomplishing both results.

Any suitable means may be employed for controlling the adjustment of the cross-head 14 within the guides 13, as set forth. As shown in the drawings, a lever 17 is pivotally supported between its ends, as at 18, Figs. 1, 3, and 4, having one end extended to and connected with the cross-head 14 and the other end engaged with a bar or lever 19, to which it is pivotally connected. The bar 19 is connected with a bell-crank lever 20, pivotally supported, as at 21, and having one end 22 extended to serve as a hand-lever to operate the same. A semicircular ratchet 23 may be provided, with which the latch 24, carried by the arm 22, operates to firmly hold and retain the parts in any desired position. By mounting the lever 17 on an oscillating arm 26, pivotally supported on the frame or other suitable part, the necessary oscillation of the disk 9 is permitted. By thus simultaneously adjusting the position or lead of the valve and its travel the steam may be cut off at any desired part of the stroke from zero to the full stroke without narrowing the steam-ports during admission.

Fig. 2 clearly shows the operation of our improvement and the effect of adjusting the supplemental valve, as described. The admission of steam to the ports 25 25 is regulated and controlled by said valve, while the admission of steam to the cylinder of the engine is controlled by the operation of the valves 3 3 in the usual manner.

Our invention is particularly applicable to horizontal marine engines, as shown, but may be readily adapted to other forms of engines. Hence we do not wish to be understood as limiting its use to marine engines only.

It is obvious that after having thus described our improvement various modifications may be made without departing from the spirit of our invention. Hence we do not wish to be understood as limiting ourselves to the exact form and construction shown. It is also obvious that our improvement may be employed upon single-acting engines, if desired, in which case one end only will be necessary.

By the term "lead" in the claims we wish to be understood as meaning the "position" of the supplemental valve when one only is employed in addition to the throw or travel of the same, and when two supplemental valves are employed that the distance between them is varied.

Having thus described our invention, what we claim as new, and desire to secure by Letters Patent, is—

1. A variable cut-off device for steam-engines, comprising a main steam-chest and its valve, in combination with a supplemental steam-chest and its valve, arranged to con-

trol the delivery of steam to the main steam-chest, and means for simultaneously adjusting both the position or lead and the travel of said latter valve, substantially as described.

2. A variable cut-off device for steam-engines, comprising a main steam-chest and its valve, in combination with a supplemental steam-chest and its valve, arranged to control the delivery of steam to the main steam-chest, said latter valve being formed in two parts, and means for simultaneously adjusting the parts to adjust the position or lead of the valve, and for regulating its travel, substantially as described.

3. In a device of the kind described, a main steam-chest and its valve, in combination with a supplemental steam-chest provided with a two-part valve, adapted to be separated to regulate the position or lead of the same, an oscillating part, a cross-head arranged upon said oscillating part adapted to be moved backward or forward with relation to the center of oscillation, and a toggle-lever extending from said cross-head to each of the parts of the valve, whereby upon shifting the position of the cross-head both the position or lead and the travel of the valve will be regulated, substantially as described.

4. In a device of the kind described, the main steam-chest and its valve, in combination with a supplemental steam-chest provided with a valve composed of two parts and arranged to control the delivery of steam to the main chest, an oscillating part, a cross-head adjustably supported upon the oscillating part adapted to be moved backward and forward relative to the center of oscillation, toggle-levers connecting the cross-head with each of the parts of the supplemental valve, and a hand-lever arranged to adjust the position of the cross-head upon the oscillating part, whereby both the position or lead and the travel of the supplemental valve may be controlled, substantially as described.

5. In a device of the kind described, the main steam-chest and its valve, in combination with a supplemental steam-chest provided with a valve parted at its middle, an oscillating part, guides 13 13, arranged upon the oscillating part, a cross-head 14, engaging the guides, toggle-levers 15 15, connecting said cross-head with the two parts of the valve, and means for adjusting the position of the cross-head 14, relative to the center of oscillation, whereby the position or lead and travel of the supplemental valve may be simultaneously adjusted, substantially as described.

6. In a device of the kind described, the main steam-chest and its valve, in combination with a supplemental steam-chest provided with a valve parted in the middle, an oscillating part, provided with guides 13 13, a cross-head 14, arranged in said guides, tog-

gle-levers 15 15, connecting said cross-head with the parts of the valve, a pivotally-supported arm 26, carrying a lever 17, having one end engaged with the cross-head, and the other end extended and engaged with a hand-lever, whereby both the position or lead and the travel of the supplemental valve may be simultaneously adjusted, and the cut-off of steam to the main steam-chest controlled, substantially as described.
